UNITED STATES PATENT OFFICE.

WARREN B. FLANDERS, OF ESSINGTON, PENNSYLVANIA, ASSIGNOR TO WESTINGHOUSE ELECTRIC AND MANUFACTURING COMPANY, A CORPORATION OF PENNSYLVANIA.

REVERSING TURBINE.

Application filed May 13, 1920. Serial No. 381,138.

To all whom it may concern:

Be it known that I, WARREN B. FLANDERS, a citizen of the United States, and a resident of Essington, in the county of Delaware 5 and State of Pennsylvania, have invented a new and useful Improvement in Reversing Turbines, of which the following is a specification.

My invention relates to turbines of the 10 marine type having ahead and reversing sets of blading, and has for its object to provide an extra row of blades, carried by the stator element, for one set of blading in order to direct steam discharged from the 15 latter with a component of motion in the direction of rotation of the rotary element, thereby avoiding braking and churning action of the steam and diminishing the liability of the turbine to overheat, especially when the reversing set is operative. 20

Another object of the invention is to provide a turbine having the ahead and reversing blading adapted to discharge into a common chamber, one of the sets of blading 25 being preferably of the impulse type and provided with an additional row of blades carried by the stator to direct the discharge in the direction of rotation of the rotor.

In the drawings, Fig. 1 is a longitudinal sectional view of a turbine having a reversing section; Fig. 2 is a diagrammatic view showing the relationship of nozzles and blading; and Fig. 3 is a velocity diagram to 30 show the velocity of steam as it traverses the different rows of blades of the impulse element.

In turbines of the marine type, the reversing section usually contains few elements 40 or rows of blades in comparison with the elements or rows of blades of the ahead section, so that the ratio of steam velocity to wheel or blade velocity is much greater, and the steam will leave the last row of 45 blades with a high velocity. Where the last row of blades of the reversing section is a moving one, the steam is discharged with a component of motion which is in a direction opposed to that of the rotor, giving a high 50 relative velocity of the rotor and the steam and thereby developing friction, the work of which opposes rotation of the rotor and is likely to produce sufficient heat to prove to be injurious. Also exhaust steam may

enter the ahead blading and result in retardation of the rotor and consequent development of objectionable heat. I, therefore, propose to provide a last row of stationary blades for the reversing section so as to reverse the direction of steam from the 55 last moving row so that it is directed with a component of motion in the direction of rotation of the rotor. Steam directed in this way, instead of developing friction which opposes the rotation of the rotor, 60 would, if it develops any friction due to relative movement, produce a moment which assists the rotation of the rotor.

In the drawings, I show a turbine of the 65 marine type having an ahead section 5 and a reversing or astern section 6 including blading carried by the rotor element 7 and the stator element 8. The ahead section is provided with the usual steam inlet and the 70 steam, after traversing and giving up its energy to the rotor blades, is discharged into the chamber 10 between the ahead and astern blading.

The astern blading is preferably of the 75 impulse type and is provided with the usual two rows of blades 13 and 15 carried by the rotor 7 and with an intervening row of stationary blades 14 carried by the stator 8. The stator is preferably provided with a 80 series of nozzles 12 adapted to discharge into the first row of moving blades 13. In addition to the ordinary arrangement of blading, I provide an additional row of stationary blades 16 carried by the stator which are adapted to receive steam 85 discharged by the last row of moving blades 15, and to direct it into the space 10 in the same direction as the direction of rotation of the rotor. A consideration of the directions of 90 rotation of the rotor and the arrangements of blading for the ahead-astern sections will show that steam from one section leaves the stationary blades 16 in a direction toward the backs of the last row of blades 11 of the other section. Since the steam is moving 95 in the same general direction as the rotor, and at a higher velocity than the rotor, it is obvious that the blades 11 will not act as braking elements for the steam discharged. Also, it will be seen that, due to 100 the direction of the discharge of steam by the blades 16 in the same direction as the direction of rotation of the rotor, there will 105

be no relative opposed motions of the rotor and the steam, whereby frictional losses and objectionable heat are developed.

Fig. 2 shows in a diagrammatic way how the steam passes through the impulse section. Steam enters through the nozzles 12, is expanded and discharged at high velocity against the moving impulse blades 13. Part of the velocity of the steam is abstracted by the blades 13 and the steam is discharged into the stationary row of blades 14 and is there redirected and discharged into the moving row of blades 15 which abstract more of the velocity of the moving steam. The steam is discharged from the last row of moving blades 15 through the stationary blades 16 and is thereby redirected so that its direction of motion has a substantially large component in the same direction as the direction of rotation of the rotor. Dotted lines "b" from the stationary blades 16 indicate the direction of flow of steam therefrom and dotted lines "a" from the moving row of blades 15 also indicate the direction of motion of steam discharged therefrom. It will be apparent, from the dotted lines "a" and "b", and the direction of the rotation of the rotor, that when steam is discharged against the direction of rotation of the rotor, objectionable heating effects are developed, possibly resulting in injury to the blading. However, when the discharge is along the lines "b", the discharged steam has a large component of motion in the direction of motion of the rotor, and thereby avoids the development of objectionable heat on account of friction.

Fig. 3 shows diagrammatically the decrease in velocity as the steam passes through the different rows of impulse blades. If it is assumed that steam is discharged from the nozzles 12 at a velocity of 3300 feet per second, it will leave the moving row of blades 15 at a velocity of approximately 1300 feet per second and will be redirected and discharged with an approximate velocity of 1200 feet per second in the direction of rotation of the rotor. By reason of the high velocity of the steam discharged by the stationary row of blades 16 of the section 6, as well as the direction of discharge, the steam is actually kept from entering the rows of blading of the section 5 and therefore greatly reduces the loss in the latter when the section 6 is in operation. This is further facilitated due to the fact the backs of the last row of blades of the inoperative section are opposed to the direction of discharge and serve to deflect the steam.

From the description of my invention as above set forth, the operation thereof will be obvious. When it is desired to render operative the section 6, steam is admitted to the nozzles 12, is expanded and discharged

through the rows of moving and stationary blades, finally entering the chamber 10 and having motion with a relatively large component in the direction of rotation of the rotor. Objectional frictional losses due to relative motion of rotating elements and the steam discharged from this section are therefore overcome. If the steam discharged from the stationary nozzles 16 should have a component velocity greater than that of the rotor, then the frictional engagement of the steam with the rotor would actually be an assistance to the rotor.

While I have shown my invention in but one form, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:—

1. In a reversing turbine, the combination of an ahead blading set and a reversing blading set having opposed exhaust ends and a series of blades cooperating with one set to insure the discharge of steam therefrom in the direction of rotation of the turbine. 90
2. In a turbine, the combination of two sets of blading adapted to exhaust in opposite axial directions into a common exhaust chamber, of a row of stationary blades cooperating with the last row of moving blades of one set of blading for directing the motive fluid to the exhaust chamber with a component of motion in the direction of rotation of the turbine. 100
3. In a turbine, the combination of two sets of blading adapted to exhaust in opposite axial directions into a common exhaust chamber, one of said sets of blading being of the impulse type, of a row of stationary blades for changing the direction of the motive fluid discharged from the impulse blades so that it has a component of motion in the direction of the rotation of the turbine. 110
4. In a turbine of the marine type, the combination of a rotor and a stator, an ahead blading set carried by the rotor and the stator, and an astern blading set spaced from the ahead blading set and carried by the rotor and the stator the sets of blading having opposed exhaust ends and adapted to discharge into a common space therebetween, and a row of redirecting blades associated with one of said sets so as to redirect the discharging elastic fluid with a component of velocity in the direction of rotation of the rotor. 115
5. In a reversing turbine of the marine type, the combination of a rotor and a stator, an ahead element comprising blading car- 130

ried by the rotor and the stator, a reversing element comprising blading of the impulse type carried by the rotor and the stator, the exhaust ends of the ahead and reversing elements being opposed and adapted to discharge into a common space, and a row of stationary blades cooperating with the last row of impulse blades of the reversing ele-

ment to redirect the elastic fluid so as to have a component of velocity in the direction of rotation of the rotor. 10

In testimony whereof, I have hereunto subscribed my name this 12th day of May, 1920.

WARREN B. FLANDERS.
